A. G. JACOBSON & A. J. BROWN.
PERMUTATION PADLOCK.
APPLICATION FILED DEC. 12, 1916.

1,274,051.

Patented July 30, 1918.

UNITED STATES PATENT OFFICE.

ARTHUR G. JACOBSON AND ARTHUR J. BROWN, OF CHICAGO, ILLINOIS.

PERMUTATION-PADLOCK.

1,274,051.

Specification of Letters Patent. Patented July 30, 1918.

Application filed December 12, 1916. Serial No. 136,518.

To all whom it may concern:

Be it known that we, ARTHUR G. JACOBSON and ARTHUR J. BROWN, citizens of the United States, residing at Chicago, in the county of Cook and State of Illinois, have invented certain new and useful Improvements in Permutation-Padlocks, of which the following is a specification.

Our invention has for its principal object 10 the provision of a permutation pad lock simple in its organization and yet practically impossible to "pick"; a pad lock adapted for use with perfect security in connection with a hasp latch by the avoidance of 15 the usual staple or like attachment; a sightly and efficient lock construction for use in connection with the doors of buildings, safes, vaults, lockers; and one which by reason of its form and internal construction 20 is of exceedingly low cost of construction. Other advantages inherent in the invention will be readily apparent to those skilled in the art from the following detailed description of a preferred and modified embodiment of the same when taken 25 in connection with the accompanying drawing upon which the description is predicated, the drawing and description being taken in an illustrative sense, and not as 30 limiting the invention other than is rendered necessary to the validity of the appended claims in view of the prior art.

In the drawing—

Figure 1 is a horizontal longitudinal section through the lock illustrating its application to a door;

Fig. 2 is a transverse section taken on the line 2—2 of Fig. 1;

Figs. 3 and 4 are respectively detail elevations of two of the three tumblers shown in transverse section in Fig. 1; and

Figs. 5 and 6 show modified forms of mounting the lock.

Heretofore it has been usual to employ 45 pad locks in connection with staples or other insecurely anchored fastening devices, and permutation and combination locks have ordinarily been of such complicated organization imperfectly protected from the weather 50 and injury as to be ill adapted for the rough usage to which pad locks are subjected. The present invention, having in view the avoidance of these objections, provides for the use of an integral portion of the lock 55 itself, that is to say the lock shackle or bolt, as the fastening device permanently at-

tached to the wall or door, and for the complete housing of the lock mechanism within the lock case sealed from external influences whether atmospheric or arising from 60 physical violence.

As herein illustrated the wall of the chamber to be protected is indicated at 11, and the door at 12, although obviously the two in their relation to the lock may be interchanged as they constitute the relatively 65 movable members to be controlled by the lock, and it is to be understood that their differentiation as herein employed is for purposes of illustration only, they being 70 equivalent for the purpose of effecting the mounting of the lock.

Having reference first to Figs. 1 to 4 inclusive, a bolt 13 is shown as permanently secured to the door 12 having its threaded 75 end extending on the inside of the door and engaged by the nut 14. The opposite end of the bolt extends exteriorly from the door to form a stud portion 15 which constitutes an integral portion of the lock itself, taking 80 the place of the ordinary shackle or bolt. Movement of the bolt 13 inwardly is prevented by means of the flanged collar 16 secured to the bolt by means of the pin 17 which projects exteriorly beyond the surface 85 of the collar. Obviously this collar may be secured to the bolt in any other approved manner or it may be formed integral therewith. The outer end of the bolt or stud 15 is provided with a series of ribs 18/90 chamfered on their forward edges as clearly shown in Fig. 5. These ribs 18 are spaced apart to form intervening transverse grooves 19 and are interrupted at points in longitudinal alinement to form the longitudinal groove 20. The ribs 18 and the intermediate grooves 19 are provided for engagement with the tumblers of the lock while the longitudinal groove 20 provides a path for the tumbler tongues when 95 brought into alinement by operation of the lock to permit removal of the lock case from the stud 15.

The lock case may be advantageously formed, as herein shown, as a spherical body 100 21 diametrically bored to receive the stud 15. The bore is enlarged as indicated at 22 to form a tumbler chamber, the entrance to said chamber on the forward face of the lock case being closed by the obturator 23 110 having a beveled face 24 provided with a scale as indicated for cooperation with a

mark 25 on the case, in the manipulation of the tumblers. The obturator may also be advantageously provided with a knurled finger piece 26 by which it is turned.

5 The bore of the case 21 fits snugly about the sleeve or collar 16, a short longitudinal groove 27 being provided to enable the case to slip over the pin 17 and to engage with the said pin 17 to prevent turning of the 10 lock case relative to the bolt.

The tumbler chamber 22 is provided at 28 with a groove extending around the same and a similar groove exteriorly provided on the obturator 23 as indicated at 29, 15 the two facing grooves providing space within which is disposed a spring 30 which effectually prevents the removal of any of the operating mechanism when the obturator is once snapped into position, although 20 permitting the obturator to be rotated freely within the lock case.

At equally spaced intervals around the inner wall of the tumbler chamber in advance of the groove 28 are a number of 25 longitudinally extending grooves 31. These may be spaced apart a distance corresponding to a certain number of the scale marks 24 on the obturator. A detector pin 32 is mounted within a recess in the obturator and pressed outwardly by means of the spring indicated at 33 so that as the obturator is rotated the pin 32 will snap into and out of the series of grooves 31 thus giving audible indication of the extent 35 to which the obturator is being moved. This facilitates the operation of the combination in a poor light and affords a ready means of determining the extent of rotation. For this purpose it is advantageous 40 to space the grooves 31 apart a distance corresponding to say five marks on the scale.

Each of the tumblers 34, 35 and 36 is approximately an annulus, each provided 45 with an inwardly projecting tongue 37. In the lock herein illustrated the inner tumbler 34 is devoid of positioning pins, whereas the intermediate tumbler 35 has two positioning pins 38 disposed one on each side 50 of the tongue 37, while the outer tumbler 36 has two positioning pins 38 arranged both on the same side of the tongue 37. The relative positions of these tongues determine the combination of the particular 55 lock. These pins 38 are arranged to be engaged by the finger pin 39 carried by the obturator, whereby the respective tumblers are brought into such position that the tongues 37 will coincide with the groove 60 20 of the stud so as to permit the said tongues to clear the ribs 18.

It will be observed that while, as stated, these tumblers are roughly in the form of annuli, yet the one-half of each tumbler is 65 in the form of a circle concentric to the

bore of the lock case, whereas the other half of the tumbler is eccentric. It thus follows that each of the tumblers 34, 35 and 36 does not entirely fill the lock case, but there remains a space, crescent-shaped, 70

on the eccentric side of the tumbler between the tumbler and the side wall of the chamber. Each of the tumblers is provided with two spaced apertures 40 for the reception of the downturned ends or calks of 75

horse shoe shaped springs 41. That portion of each spring opposite its points of engagement with the tumbler extends beyond the eccentric side of the tumbler and bears against the side wall of the tumbler 80

chamber so as to maintain the tumblers yieldingly pressed in the opposite direction with their concentric sides in engagement with the wall of the chamber. These 85 springs serve the double purpose of washers between the tumblers and as resilient means for bearing against the side wall of the chamber to frictionally prevent rotation except as positively impelled by the obturator finger.

It will be observed that each 90 of the tumblers has a thickness corresponding substantially to the transverse grooves 19 intermediate the ribs 18 while the springs 41 are of a thickness corresponding to that of the ribs 18, the tongues 37 of the tumblers rotating within the grooves 19 until they are brought into alignment into a position to be freed from the ribs 18 by the grooves 20 and to pass outwardly off the studs. When assembled within the chamber 95 of the lock case each of the tumblers rest against the spring of the next adjacent tumbler in such manner as to prevent any disarrangement of the parts. Each of the tongues 37 is chamfered on one side 100 for co-operation with the chamfered edge of the ribs 18 while the other side of the tongue as also of the ribs is abrupt whereby to permit the lock case and tumbler to be pushed on to the stud regardless of 105 the positioning of the tumbler tongue, the springs yielding to permit the tongues to ride over the ribs in one direction but to effectually preclude this action in any attempt to withdraw the lock case from the 110 stud.

The lock organization having been described, the manner of its application to the door will now be referred to. As illustrated in Fig. 1, an angle iron 42 is bolted 115 as indicated at 43 on the inner side of the wall 11 and at its outer edge has hinged at 44 a hasp 45 apertured or bifurcated in its free ends at 46 to embrace the bolt 13 or the collar 16 mounted on said bolt. The 120 door 12 having been swung to its closed position, the hasp 45 is swung over to embrace by its end 46 the projecting stud 15 and the lock case 21 is then pushed on to the end of the stud, the tumblers yield- 125 130

ing under the opposition of the springs 41 to permit their tongues 37 to ride over the ribs 18 and to engage within the grooves 19. The pin 17 is housed within the groove 27 secure from interference, the lock 21 cannot rotate on the stud 15 and can only be removed therefrom by the intelligent operation of the obturator 23, bringing the tongues 37 into alinement with each other 10 and with the groove 20 of the stud.

In Fig. 5 the same lock is shown, the bolt portion thereof being mounted as in Fig. 1 upon the door, but the lock case 21 is in this instance carried by the hasp 45^a, the 15 bore of the lock itself taking the place of the apertured or bifurcated end of the hasp. This construction has the advantage that the lock case is associated permanently with the building and is not liable 20 to be lost as might result in the first construction although, obviously, the lock case 21 as shown in Fig. 1 could be provided with a chain for attaching it to the door 12.

In Fig. 6 a still further form of mounting is shown, the lock bolt 13 being in this instance permanently attached to the wall 11, while the lock case 21 is also permanently attached to the door 12, the employment 25 of a hasp being done away with entirely and the lock case 21 serving as a handle for the opening and closing of the door. The operation is precisely the same.

We claim:

1. In a permutation lock, the combination 35 of a case having an interior chamber, a series of tumblers therein of less diameter than said chamber, interposed spring washers each connected with one of the tumblers and arranged to press the tumbler against 40 the chamber wall, the case and tumblers having an axial bore, a bolt adapted to enter the bore, the tumblers and bolt having co-operating ribs and grooves, and exteriorly arranged means to manipulate the tumblers.

45 2. In a permutation lock, the combination of a case having an interior chamber, a series of tumblers therein of less diameter than said chamber, interposed U-shaped 50 spring washers each connected at their ends with one of the tumblers and bearing at the bend on the chamber wall to press the tumbler against the opposite wall, the case and tumblers having an axial bore, a bolt adapted to enter the bore, the tumblers and bolt having co-operating ribs and grooves, and exteriorly arranged means to manipulate the tumblers.

55 3. In a permutation pad lock, the combination of a case having an interior chamber, a series of disk tumblers therein of less diameter than said chamber, interposed U-shaped 60 spring washers each connected at their ends with one of the tumblers and bearing at the bend on the chamber wall to press the tumbler frictionally against the

opposite wall, the case and tumbler having an axial bore, a bolt adapted to enter the bore, the tumblers and bolt having co-operating ribs and grooves, and exteriorly arranged means to manipulate the tumblers. 70

4. In a permutation lock, the combination of a case having an interior chamber, a series of disk tumblers therein of less diameter than said chamber, interposed U-shaped 75 spring washers each connected at its end with one of the tumblers and bearing at the bend on the chamber wall to press the tumbler against the opposite wall, the case and tumbler having an axial bore, a bolt adapted to enter the bore, each of the 80 tumblers having an inwardly projecting tongue, the bolt having ribs and grooves for co-operation with the tongues of the tumblers, exteriorly arranged means to manipulate the tumblers. 85

5. In a permutation lock, the combination of a case having an interior chamber, a series of disk tumblers therein of less diameter than said chamber, interposed U-shaped 90 spring washers each connected at its end with one of the tumblers and bearing at the bend on the chamber wall to press the tumbler against the opposite wall, the case and tumbler having an axial bore, a bolt adapted to enter the bore, each of the tumblers having an inwardly projecting tongue, the bolt having ribs and grooves for co-operation 95 with the tongues of the tumblers, exteriorly arranged means to manipulate the tumblers comprising an obturator for one end of the bore having a scale co-operating with a mark on the case. 100

6. In a permutation lock, the combination of a case having an interior chamber, a series of tumblers therein having a central 105 bore and eccentric periphery, the minor diameter of each tumbler being less than the diameter of the chamber, U-shaped spring washers interposed between the tumblers and engaged therewith at their ends, the spring washers bearing at the bend on the chamber wall to press the tumblers against the opposite wall, a bolt having tumbler engaging ribs and grooves adapted to enter the bore of the tumblers, each of the tumblers having 110 an inwardly projecting tongue for engagement with the ribs and grooves of the bolt, and exteriorly arranged means to manipulate the tumblers. 115

7. In a permutation lock, the combination 120 of a case having an interior chamber, a series of tumblers therein of less diameter than said chamber, interposed spring washers each connected with one of the tumblers and arranged to press the tumbler against 125 the chamber wall, the case and tumbler having an axial bore, a bolt adapted to enter the bore, the tumblers and bolt having co-operating ribs and grooves, and exteriorly arranged means to manipulate the tumblers, 130

- and means operating audibly to indicate the extent of rotation.
8. In a permutation lock, the combination of a case having an interiorly arranged chamber, a series of tumblers therein, the tumblers having longitudinally aligned apertures, a bolt having tumbler engaging ribs and grooves and adapted to enter the apertures, a tumbler operating obturator arranged in one end of the chamber and accessible from without, the obturator and lock case having coöperating scale markings to determine the extent of rotation of the obturator, and means operating audibly to indicate the extent of rotation, said audibly operating means comprising a spring pressed pin mounted in the obturator and arranged to snap into equally spaced grooves on the case.
- 20 9. In a permutation lock, the combination of a case having an interior chamber, a series of tumblers therein, the case and tumblers having an axial bore, a stud adapted to enter the bore, each of the tumblers having an inwardly projecting tongue and pin,
- 5 the stud having tumbler engaging ribs and grooves for engaging with the tongues, a tumbler-actuating obturator having a finger pin arranged to enter the bore of the tumblers and to engage the pins. 30
- 10 10. In a permutation lock, the combination of a case having an interior chamber, a series of tumblers therein, the case and tumblers having an axial bore, a stud adapted to enter the bore, each of the tumblers having an inwardly projecting tongue and pin, the stud having tumbler engaging ribs and grooves for engaging with the tongues, a tumbler-actuating obturator having a finger pin arranged to enter the bore of the tumblers and to engage the pins, the obturator and case having coöperating scale marks to visually indicate the extent of rotation and also provided with means to audibly indicate the extent of rotation. 35 40
